UNITED STATES PATENT OFFICE.

FRIEDRICH CARL VOM BRUCK, OF DUSSELDORF, GERMANY, ASSIGNOR TO THE FIRM OF FRIEDR. CARL VOM BRUCK, OF VELBERT, GERMANY.

BOLT FOR DOORS AND WINDOWS.

1,023,455.

Specification of Letters Patent.

Patented Apr. 16, 1912.

Application filed April 13, 1910. Serial No. 555,205.

To all whom it may concern:

Be it known that I, FRIEDRICH CARL VOM BRUCK, a subject of the German Emperor, and residing at Dusseldorf, Germany, have 5 invented certain new and useful Improvements in Bolts for Doors and Windows, of which the following is a specification.

The subject-matter of my invention is an improved bolt for doors and windows.

10 In well-known bolts for securing doors and windows the sliding bolt is guided in special keepers or guides which clasp the bolts. It may happen that, when unlocking or locking the door or window, the 15 bolt pinches the finger between the keeper and the handle of the bolt, or injures the finger at the projecting edges of the keeper. The guiding portions of the bolt are free and therefore exposed to dust and dirt, so 20 that the sliding bolt soon moves with difficulty, and when a spring is arranged under the bolt in the customary manner, the bolt is pressed away from the plate so that here also a space accessible to dust and the like 25 is produced.

A primary object of my invention is to remedy these defects. I attain this end by providing in the sliding bolt or in its base-plate a longitudinal chamber, into which 30 guide pins for the sliding bolt extend and serve for holding the spring which is arranged between the pins and presses the bolt and base-plate against one another.

Two illustrative embodiments of my invention are represented by way of example 35 in the accompanying drawings wherein:—

Figure 1 is a top plan view of one form of my improved bolt; Figs. 2 and 3 are longitudinal sections through the center of 40 the bolt in two different positions thereof, and Fig. 4 is a top plan view in a position corresponding to Fig. 3, the cover having been removed; Fig. 5 is a longitudinal section through a modified form of bolt; Fig. 45 6 is a cross-section in the plane A—B in Fig. 5, and Fig. 7 is a top plan view of the plate of the bolt according to Figs. 5 and 6.

Referring firstly to Figs. 1 to 4, on the base-plate *a* I provide two guide pins *b*, *b*, 50 having heads. The sliding bolt comprises the plate *d* having slots *c*, *c*₁ and the top part or cover *f* inclosing the same and form-

ing therewith a chamber *h*. The hollow sliding bolt is guided by the two pins *b*, *b*₁ which pass through said slots. In the 55 chamber *h* is located the spring *g*; this serves for pressing against the sliding bolt, is suitably held at its two ends by the pins *b*, *b*₁ and is tensioned in such manner between these that it presses the bolt tightly 60 against the base-plate. By means of the rounded projection *i* under the spring pressing on the part *d* of the sliding bolt, the latter is secured, in its unlocked and locked positions and is prevented from being moved unintentionally owing to said projection snapping into recesses or holes *o* and *o*₁ in the member *d*. The two parts *d* and *f* are preferably connected at their 65 front ends by means of a special rivet *r* 70 and at the rear by the pin of the handle or grip *k*.

In the illustrative embodiment shown in Figs. 5 to 7 the chamber *h*, is in the hollow base-plate *a* which has slots *c*, *c*₁; the guide 75 pins *b*, *b*₁ are secured in the sliding bolt *f*, extend into the chamber *h*, and carry between them the spring *g*. The guiding parts are covered by the sliding bolt which is pressed closely against the plate *d* by the 80 spring.

Owing to the described arrangements a perfectly smooth bolt without any projecting guiding portions is made, so that fingers can no longer be jammed or pinched 85 nor hands injured thereby. The sliding bolt fits closely against the base-plate, the bolt has a good appearance, its guiding parts are protected from dust, and when any of the sliding parts are lubricated, the lubricating agent cannot be touched and is prevented from soiling other articles.

I claim:—

1. In a bolt of the character described, the combination, with a base plate, of a 95 sliding bolt slideable thereon, and guiding means comprising a tensioned spring securing the bolt on, and pressing the bolt against, the base-plate, said guiding means being protected from dust by the bolt.

2. In a bolt of the character described, the combination, with a base-plate, of a sliding bolt slideable thereon, guide pins movably securing the bolt on the base-plate, and a

spring carrying a projection, said spring being tensioned between said pins and pressing the bolt against the base-plate.

3. In a bolt of the character described, 5 the combination of a base-plate, a hollow, slotted bolt having recesses slidable thereon, two pins fixed on said base-plate projecting into said hollow bolt, and a spring carrying a projection, said spring being tensioned

between said pins in said bolt, the projection 10 being arranged to enter into said recesses in the end positions of the bolt.

In testimony whereof, I affix my signature in the presence of two witnesses.

FRIEDRICH CARL VON BRUCK. [L. s.]
